UNITED STATES PATENT OFFICE

WILLIAM E. BIGGS, OF KNOXVILLE, TENNESSEE

UNDERFEED STOKER

Application filed April 30, 1928. Serial No. 274,059.

This invention relates to underfeed stokers for furnaces and has for its object to improve the grate construction in such furnaces, facilitate the feed of the fuel, and to avoid the formation of clinkers on the walls of the furnace, as well as to improve the construction of the furnace in other particulars which will appear hereinafter.

With these objects in view, the invention consists in a furnace of this type having the usual or any suitable retort extending longitudinally through the furnace with a series of grate bars suitably supported on either side of the retort, which grate bars in the aggregate form on each side of the retort fuel supporting surfaces whose general angle of inclination is downward in a lateral direction from the retort. The grate bars are especially constructed so that individual members can be readily removed, when burned or worn out, and replaced by new members without disturbing the construction of the furnace as a whole or the remaining portions of the grate surface. Furthermore, the invention includes an especially constructed upwardly inclined interior end of the retort adjacent the end wall of the furnace, combined with means for injecting steam, preferably exhaust steam, in proximity to the end wall for the purpose of cooling the same and preventing the formation of clinkers thereon.

Preferably certain of the grate bars are constructed to reciprocate from and toward the retort, other members intermediate the reciprocating members being held in stationary position, and means are provided for reciprocating said movable members which means are actuated from the main source of power for feeding the fuel into the retort. This source of power may be any suitable mechanical or electric drive, steam or gas engine, etc., and as shown includes a steam-actuated piston with a plunger head for feeding the fuel from a suitable hopper into the retort, while preferably connected to said plunger head is a bar extending longitudinally of the bottom of the retort, having attached thereto feeding abutments, as is usual in such constructions.

For the purpose of regulating the movements of the actuating piston, where a steam-actuated piston is employed, and of preventing the striking of said piston against the opposite ends of the cylinder within which it works, suitable means are provided for automatically controlling its movement by the exhaust steam from the cylinder.

The actuating piston for the pusher head has an intermittent reciprocating motion—that is, a forward stroke followed by a dwell, and a rearward stroke likewise followed by a dwell, and means are provided for effecting this intermittent motion and producing the desired dwell. Preferably such means consist of a dashpot provided with a liquid, as oil, which is permitted to have a regulated flow from one end of the dashpot to the other end, that is, to opposite sides of the dashpot piston. Other detailed features of the invention will be referred to hereinafter.

The invention is shown in the accompanying drawings in which

Figs. 1 and 1a together constitute a longitudinal, central sectional view through the furnace, the retort and the actuating piston and its connections;

Fig. 2 is a top plan view of the steam piston and its connections with the pilot valve mechanism shown in horizontal section;

Fig. 3 is a front elevation of the furnace with the air chamber or wind-box beneath the same;

Fig. 4 is a central, transverse vertical section of the furnace;

Fig. 5 is a view in perspective showing the connections for driving the grate bars and other moving parts;

Fig. 6 is a detailed perspective of a dumping plate;

Fig. 7 is a like view of the retort end cap;

Fig. 8 is an expanded perspective view showing the arrangement of the stationary and movable grate bars;

Fig. 9 is a broken detail of a portion of the retort; and

Fig. 10 is a plan view of a portion of the

fuel supporting bed showing the arrangement of the grate bars.

Referring to Figs. 1 and 3, 1 indicates a chamber to which air under pressure is supplied from any suitable source, on each side of which is provided a lateral chamber 2, 2', suitable dampers 3 being interposed between the chambers 2 and 2' whereby the passage of air under pressure from the chamber 1 to the chambers 2 or 2' as the case may be, may be effectively controlled. Immediately above the air chamber 1 is a retort 4 extending from the front of the furnace to the rear wall 5. Preferably this retort is in the form of a long trough or channel, U-shaped in cross section as shown in Fig. 4, and at its upper edges terminates in laterally extending flanges 4'. The wind-box 1 opens upwardly into the space 6, Fig. 4, extending the full length of the retort 4 and laterally approximately to the outer limits of the fuel supporting surface, as will be readily understood from an inspection of Fig. 4. On either side of the retort two longitudinally extending supports 7, 7', extend through the furnace, preferably in the form of angle bars, which bars form the supports for the outer ends of the grate bars, the inner ends of which rest upon the flanges 4' of the retort. These flanges of the retort are provided with downwardly extending lugs 4'', see Fig. 9, which lugs are suitably spaced for a purpose hereinafter to be described.

35 The construction of the grate bars will be best understood from an inspection of Figs. 4, 5, 8 and 10. As here shown, three of the grate bars are secured together so as to form a single unit and are so mounted as to remain stationary, while a movable bar is mounted between compound units of stationary bars and is arranged to be reciprocated longitudinally of the bar for the purpose of moving the fuel laterally to either side from the retort. Referring to Fig. 8, the three stationary grate bars 8, 8' and 8'' are provided with an upwardly extending portion forming approximately a continuation of the walls of the retort 4 and with laterally and downwardly inclined portions extending out to the supporting bars 7'. Each of these grate bars 8, 8' and 8'' has one plane side surface, and the other side is provided with a series of ribs 9, 9' and 9'', the several ribs being spaced apart to form air passages for the supply of air to the fuel bed to support combustion. The ribs 9 are inclined outwardly and upwardly from the retort. The ribs 9' are approximately vertical, while the ribs 9'' are also inclined outwardly and upwardly but at a very small angle. Moreover, the air passages between the ribs 9 are deeper than the air passages between the ribs 9' and the air passages between the ribs 9'', to the end

that the amount of air supplied to the fuel bed will be greater in that portion of the grate bar adjacent the retort, and will gradually decrease in cross section, and consequently in the amount of air supplied to the fuel, outwardly towards the outer ends of the grate bars. All of the grate bars 8, 8' and 8'' are provided with downwardly extending webs 10, and the lower inner ends of these webs 10 on the grate bars 8 and 8'' are provided with lugs 10'. These three bars 8, 8' and 8'' are assembled in the manner shown in Fig. 8 and are secured together as a unit by bolts 11 passing through the three bars, each of the bars having a plane face adjacent the rib face of the next bar, and when thus assembled, as shown in Fig. 8, there is provided a series of air channels 12 between the bars.

35 The movable bar 13, Fig. 8, is provided with ribs exactly similar in arrangement, spacing, etc., as has just been described in connection with the ribs on the stationary bars 8, 8' and 8''. The bar 13 is provided with a central downwardly extending web 14 from which web there extends a lug 15 forward toward the retort. This web 14 has cut therein an inverted U-shaped opening 16 for a purpose hereinafter to be described.

Referring now to Figs. 8 and 10, it will be seen that the outer ends of the webs on the bars 8 and 8'' are somewhat shorter than the outer end of the web on the bar 8', and when these three bars are bolted together they are placed in position by inserting the lugs 10, 10' under the flange 4' of the retort 4 between the lugs 4'' on said flange, and then dropping the outer ends of the three bars thus secured together onto the upper surface of the bars 7, 7', the ends of the webs 10 of the bars 8 and 8'' coming against the inner edges of the flanges on the bars 7 and 7', while the outer end of the web on the bar 8', which as above indicated is slightly longer than the other webs, drops through a notch 17, Fig. 10, formed in the flange of the bars 7 or 7', as the case may be. When this is in position it will be seen that the three grate bars bolted together cannot move either in a lateral or longitudinal direction, being held by the long web on bar 8' engaging the notch 17 against lateral movement of the outer end, and by the lugs 10' engaged between the lugs 4'' at the inner end. The bars cannot be lifted at the inner ends because the lugs 10' are engaged under the flange 4'. Nevertheless the group of bars can be quickly and readily removed by raising the outer end until the webs thereof clear the flanges on the bars 7, 7'. The web 14 on the movable bar 13 terminates at its outer end so as to leave an intervening space between the end of the web and the supporting angle bars 7, 7' to the

end that the bar 13 may be reciprocated or moved outward until stopped by the end of the flange 14 impinging against bar 7, as will be clearly understood from an inspection of Fig. 4. Extending laterally from the ends of the grate bars outward toward the walls of the furnace are dump plates 18, provided with the usual or any suitable means for lowering them to dump ashes into the lateral chambers 2, 2'. Said dump plates 18 are provided with suitable air passages 19, for the passage of air to support combustion of any of the unconsumed fuel that may reach said dump plates. The air for supporting combustion on these dump plates is admitted from the chamber 6 through the dampers 3, 3' to the chambers 2, 2' as will be readily understood from an inspection of Fig. 4.

For the purpose of supplying fuel to and feeding the same through the retort in the furnace, there is provided the usual or any suitable hopper 20 in which the fuel is placed, which hopper opens into the outer end of the retort as shown in Fig. 1. Fuel is fed from the hopper 20 to the retort by means of a suitable reciprocating plunger actuated by any suitable source of power. In the form shown, the plunger is operated by a steam engine, and to this end a steam cylinder 21 is suitably supported in front of the hopper, in which cylinder plays a piston 22 whose piston rod 23 extends toward the retort and has on its end a plunger 24. The fuel is fed from the bottom of the hopper 20 in front of the plunger 24 and by said plunger is forced forward into the retort, and a push bar 23' is secured to the plunger and extends along the bottom of the retort, as will be readily understood and as is usual in this art. This bar is provided with suitably spaced feed blocks or shoulders 23'' for advancing the fuel through the retort.

The construction of this plunger and associated parts is preferably such that the plunger head or pushing face may be removed and replaced in case of wear, especially between the upper edge thereof and the lower edge of the hopper 20 where the plunger passes into the retort. Referring now to Figs. 1 and 5, the plunger 24 comprises a hollow cylindrical casing threaded at its rear or outer end on a cross-head 25 which is loose on the piston rod 23 and normally abuts against a shoulder 25' formed thereon. At the other end of the plunger, a head or plate 91 has a portion 92 of reduced diameter fitting within the end of the plunger casing and is held from turning relatively thereto by a pin or pins 93. The end of the piston rod 23 passes through the head 91, and nuts 94 on the end of said rod serve to clamp the assembly of cross-head casing and plunger head rigidly together.

against the shoulder 25'. To permit of ready attachment to or removal from the plunger of the push bar 23', the piston rod 23 passes loosely through a supporting member 95, which is clamped against the head 91 by the nuts 94 and is prevented from turning relatively to the latter by a pin or pins 96. The member 95 has a projecting boss 97 which is provided with a tapped, threaded opening 98 to receive the threaded end of the push bar 23'. Should it be desired to remove or replace the push bar or plunger head, it is only necessary to remove the nuts 94, when said members may be freely disengaged.

The cross-head 25 has pivoted to its outer ends two links 26, 27, extending forward and connected respectively to the long arms, 28 and 29, of two bell-crank levers fulcrumed on a suitably supported bearing 30, said levers having their short arms 31 and 32 extending forward where they are pivotally connected to two vertical rods 33 and 34. The upper ends of the rods 33 and 34 are connected respectively to rocking levers 35 and 36, which are mounted to turn freely on shafts 37 and 38 which extend longitudinally through the furnace beneath the grate bars and on opposite sides of the retort, suitable bearings (not shown) being provided for the support of said shafts. Keyed to the shafts 37 and 38 are upwardly extending lever arms 39 and 40. A rod 41 is mounted in the upper ends of the lever arms 39, and a rod 42 is mounted in the upper ends of the arms 40. These rods 41 and 42 extend through and engage in the U-shaped grooves 16 of the webs of the movable bars 13, as will be understood from an inspection of Fig. 4.

Fixed on the forward ends of the rock shafts 37 and 38 are two housings 43 and 44, into which housings the levers 35 and 36, pivoted on such rock shafts, extend, and within which said levers are free to move within limits which are determined by suitable abutments in the form of screws 45, 46. The lever 35, for example, can move upward without moving the rock shaft 37 until it contacts with the screw 45, after which the housing 43 on the rock shaft 37 and the lever 35, move upward together. On the reverse or downward movement of the lever 35 said lever moves without rocking the shaft 37 until it contacts with the lower screw 45, after which the shaft moves with and is rocked by the lever 35. The same action of the parts is true in connection with the shaft 38 and the lever 36.

As the piston rod 23 moves inward it will impart a downward thrust to the links 33 and 34, and will rock the shafts 37 and 38 in a direction to move the movable grate bars 13 inward. On the other hand, when the piston rod 33 is moved outward, that

is from right to left in Fig. 5, the links 33 and 34 will have an upward thrust imparted thereto, and the shafts 37 and 38 will be rocked so as to move the rods 41 and 42 outward and with them the movable grate bars 13. The result of this will be an outward movement of the movable bars of the grate on either side, and then an inward movement of said bars, with the result that the 10 fuel bed will be moved outward.

Steam is admitted to the cylinder 21 through an inlet pipe 50 controlled by a suitable slide valve 51. The position of this slide valve 51 is controlled by a rod 52 carrying pistons 53, 54 at the ends thereof, which pistons are reciprocated in cylinders 55, 56 by steam admitted to said cylinders through steam channels 57, 58, Fig. 2, which channels are controlled, in turn, by a slide 15 valve 59 attached to a rod 60. This rod 60 has adjustable stops 61 and 62 thereon, between which plays a sliding sleeve 63, connected by a link 64 to a lever 65 keyed on a shaft 66 mounted to turn in bearings suitably supported on the framework of the stocker. This shaft 66 has a downwardly extending lever 67 slotted at its lower end, as at 68, and engaging a stud 69 extending outward from the cross-head 25. The reciprocation of the cross-head 25 rocks the lever 67 backward and forward and this imparts a backward and forward thrust to the rod 60, thereby shifting the valve 59 so as to uncover first one and then the other 30 of the steam passages 57 and 58. The usual or any suitable exhaust ports are provided in the respective cylinders 55 and 56.

The movements of the pistons 53 and 54 are controlled by a dashpot consisting of a 40 cylinder 70, within which plays a piston 71 connected by a rod 72 to the pistons 53 and 54. Any suitable liquid, as oil, is supplied to the cylinder 70 on the opposite sides of the piston 71 from a suitably elevated reservoir 72, Fig. 1, from which extends a pipe 73 which, preferably adjacent to cylinder 70, is provided with two branches 74 and 75, one extending to either side of the piston 71 into the cylinder 70. Check valves 76 and 50 77 are provided in the branches 74 and 75, which branches are connected by a bypass 78 provided with a suitable valve, as a needle valve 79, which valve is either manually manipulated or can be connected to a 55 suitable damper regulator through the lever 80 and the cable 81.

Exhaust steam is led out from the cylinder 21 through the exhaust pipe 82, by means of the usual admission and exhaust passages 60 83 and 84 and the slide valve 51. Since the slide valve 51 has a retarded action, the piston 23 is likely to slap against the end of the cylinder at the end of its stroke before the valve 51 has been reversed to admit steam 65 behind the piston. To prevent this, suitable

cushioning means are provided, which in the embodiment shown are applied only to the outward stroke of the piston since the resistance opposed by the fuel is sufficient for this purpose on its inward stroke. As 70 shown, the admission and exhaust port of passage 83 at the outer end of the cylinder is spaced from the end of the latter and is covered by the piston 23 before it reaches the end of the outward stroke. This prevents further exhaust through passage 83, and forms a compression chamber which acts as a cushion, in which sufficient pressure is created to start the return stroke of the piston as soon as slide valve 51 has opened 80 passage 84 to the exhaust pipe 82. The initial return stroke of the piston caused by this pressure can readily be made sufficient to uncover the port of passage 83 and admit live steam behind the piston. 85

As the piston moves in one direction in the cylinder 21, it acts to shift the pilot valve 59 so as to admit steam behind one of the pistons 55, 56, which pistons are moved over slowly. As the dashpot piston moves therewith, the rate of movement is determined by the setting of the needle valve 79. When the pistons 55 and 56, as the case may be, have shifted the slide valve 51, the reverse action takes place, but it will be observed that there is necessarily a dwell in the reciprocations of the piston 22, depending upon the time necessary for the piston 71 in the dashpot to pass the oil from one side of the piston 71 through the needle valve 79 to the other side sufficiently to permit the slide valve 51 to be moved into the reverse position. 95

The exhaust pipe 82 is led into the furnace along one side of the retort to its extreme inner end, and then across and under the upwardly inclined end thereof adjacent to the wall 5. The end portion of the pipe is perforated so as to permit the steam to rise and impinge upon the wall beneath the upwardly inclined end of the retort and to pass upward through suitable openings therein, and thus serve also to cool the wall above the retort. 105

For the purpose of providing an efficient and yet readily removable cap to the upwardly inclined end of the retort, the construction shown in Figs. 1a and 7 is provided, such construction taking the form of a cap 85. This cap is preferably in the form of a casting having lugs 86 on the lower portion thereof which engage under a flange 87 on the upwardly inclined portion of the retort, and also has a downwardly extending flange 89 abutting the wall 5 of the furnace. This cap is provided with ports or openings 90 for the passage of steam upward therethrough. The steam escaping from the pipe 82 serves to keep the cap, the wall above the cap and the wall below the cap, cool. 115 120 125

This cooling effect on the wall prevents the formation of clinkers thereon and also prevents the destruction of the cap itself.

By the use of the grate and grate bar construction herein described, and the cap at the inclined end of the retort, these parts, which are liable to become burned out in use, may be readily removed as individual elements, either for repair or replacement by new parts, and this without disturbing the construction of the furnace or the grate as a whole. Moreover, these individual grate bars, as well as the compound grate bar unit and the inclined cap constitute in and of themselves structures capable of manufacture separate from the manufacture of the furnace as a whole, but of which they constitute elements in combination, and such elements are therefore hereinafter claimed per se.

It will furthermore be appreciated that the means for cushioning the stroke of the power piston is one of exceedingly simple design and the same is true of the design and construction of the means for supplying the dashpot structure of the slide valve with fluid and regulating the rate of passage of said fluid from one side to the other of the piston of the dashpot.

While the invention as a whole has been described herein with considerable detail, it will of course be understood by those skilled in the art that variations can be made within the spirit of the claims hereto appended, and such variations are intended to be covered by such claims.

What is claimed is:

1. In an underfeed stoker, the combination of a retort having laterally extending flanges at its top, with a plurality of grate bars whose inner ends rest upon said retort flanges, lugs on said grate bars engaging the under sides of said flanges, means supporting the outer ends of said grate bars, downwardly extending shoulders on said grate bars opposite said supporting means, and means restraining said grate bars against movement longitudinally of the retort, whereby the grate bars are maintained in spaced relation and restrained against vertical movement at the ends thereof adjacent the retort.

2. In an underfeed stoker, the combination of a retort having laterally extending top flanges, and means feeding fuel along said retort, with a grate comprising a plurality of grate bars forming a stationary unit whose retort end is supported by said retort flange and a grate bar movable transversely of the retort and whose retort end is supported by said flange, means restraining the inner ends of said unit and movable grate bar against vertical movement, lugs on said unit and said movable bar engaging the under side of said flange, means sup-

porting the outer ends of said unit and said movable bar, a downwardly extending shoulder on said unit engaging said supporting means and restraining the said unit against movement transverse to the retort, means reciprocating said movable bar transversely to the retort, a stop limiting the reciprocation of said movable bar, and means restraining said unit and said movable bar against movement longitudinally of the retort.

3. In an underfeed stoker, a retort, a grate composed of a series of grate bars extending transversely thereof and each having one grooved and one plane side face, means restraining the inner or retort ends of said bars from vertical movement, means restraining a plurality of said bars from movement transverse to the retort and from movement longitudinally thereof, transversely extending movable bars interposed between said last named bars, and means imparting movement to said movable bars, transverse to said retort.

4. In an underfeed stoker, the combination of a retort, means feeding fuel along the same, and an air chamber beneath said retort, with a grate having bars extending transversely of the retort the retort ends of which bars are supported by said retort, means supporting the outer ends of said bars, said grate comprising stationary compound units alternating with single movable bars, means reciprocating said movable bars transversely of the retort, and means restraining the retort ends of said units and said bars from vertical and from movement, longitudinally of the retort.

5. In an underfeed stoker, the combination of a retort and means for feeding fuel thereto, of a series of grate bars on each side of the retort and extending outwardly therefrom, each of said bars having a first portion extending upward and slightly outward from the retort, a second portion extending outward and slightly downward from said first portion, a third portion extending outward and sharply downward from said second portion and a fourth portion sloping outward and gently downward from the third portion, said second portion having approximately vertical air conducting grooves formed in one face of the bars and another portion having approximately horizontal grooves formed in said face.

6. In an underfeed stoker, the combination of a retort and plunger means for feeding fuel thereto of two series of grate bars, one on either side of said retort, means restraining the inner or retort ends of said bars from vertical movement, means restraining said bars from movement longitudinally of the retort, and means supporting the outer ends of said bars while leaving said ends free for upward movement.

7. In an underfeed stoker, a combination of a retort, a fuel push bar, a power actuated plunger rod, a hollow plunger mounted thereon, a removable plunger face mounted on said plunger rod and closing the forward end of the plunger and means connecting said push bar to said removable plunger face.

In testimony whereof I have signed this
10 specification.

WILLIAM E. BIGGS.
